US00D711528S

(12) **United States Design Patent**
Grunstad et al.

(10) **Patent No.:** **US D711,528 S**
(45) **Date of Patent:** **** Aug. 19, 2014**

(54) **DRY POWDER INHALER**

(71) Applicant: **Oriel Therapeutics Inc.**, Durham, NC (US)

(72) Inventors: **Jerome A. Grunstad**, Inver Grove Heights, MN (US); **Charles Buckner**, Chapel Hill, NC (US); **Cyan Godfrey**, Chapel Hill, NC (US); **Daniel Deaton**, Apex, NC (US); **Andrew J. Valentine**, Raleigh, NC (US); **Margaret F. Butler**, Raleigh, NC (US); **Thomas W. Ruckdeschel**, Cary, NC (US)

(73) Assignee: **Oriel Therapeutics, Inc.**, Durham, NC (US)

(**) Term: **14 Years**

(21) Appl. No.: **29/454,143**

(22) Filed: **May 7, 2013**
